FOLDING POCKET KNIFE

Torger Tveit, Lidgerwood, N. Dak.

Application July 5, 1947, Serial No. 759,044

2 Claims. (Cl. 30—161)

1

The present invention relates to pocket knives and the like and particularly to folding knives in which a cutting blade is arranged to be folded into the handle when not in use.

The main object of my invention is to provide a folding pocket knife of the type indicated which has facilities for extending the knife blade beyond the working end of the handle for use and for concealing said blade within the handle when in idle condition.

An ancillary object is to provide a knife of this character with a split bolt having a blade pivotally mounted between the two ends thereof and being also capable of accommodating a locking member thereon for retaining said blade in open and closed positions, at will.

It is also an object to provide a knife of the mentioned character with a split lock nut for locking the knife blade in either one of its attained positions to render the knife safe.

Other objects and advantages will appear more fully in detail as this specification proceeds.

In order to bring out the features of the invention in clear and comprehensible manner, the same is illustrated in the accompanying drawing forming part hereof, and in which,

Figure 1 is an elevation of a knife made according to the invention and embodying the salient features thereof in a practical form, the knife being shown closed.

Figure 2 is a side elevation of the same knife.

Figure 3 is a transverse section of the knife taken on the line 3—3 in Figure 1.

Figure 4 is a top or plan view of the knife shown in Figure 1.

Figure 5 is a transverse section taken on line 5—5 in Figure 2.

Figure 6 is a vertical fragmentary section of the upper end of the knife taken on line 6—6 in Figure 4.

Figure 7 is a longitudinal section taken when the knife blade is extended into useful position, a second blade still being disposed in the closed position within the handle.

Throughout the views, the same reference numerals indicate the same parts.

Pocket knives and hunting knives are often useful only if tolerably large, but if made with the blade rigid with the handle, they occupy considerable space and constitute a definite hazard to have around with an exposed sharp blade. Of course, covers for such knives are often used, but they then occupy even more room and are bulky enough to present a problem to the person carrying them with other supplies on a trip.

2

In order to facilitate carrying a knife in small compass it is now proposed to hinge the blade in the end of the handle and provide a special locking means for holding the blade rigid in either open or closed condition.

Hence, in the practice of my invention, and referring now again to the accompanying drawing, a knife, generally indicated at 9, includes an elongated metal member taking the general form of a bolt 10 having a deep side slot 11, this slot being cut all the way through at the two ends, and in fact, the slot is preferably carried entirely through along the whole length of the bolt-formed member which is thus divided into two similar opposite members 12, 13. Between these opposed members are disposed a pair of knife blades 14, 15, pivoted independently at the ends thereof to the ends 16, 17, 18, 19 of said members 12, 13 by transverse pivot pins 20, 21, passing through the knife shanks 22, 23 in such fashion that these pins are disposed at one end midway between a pair of threads upon the knife members 12 and 13, and at the opposite ends terminate in line with a thread each. The outer convex portions of the ends 16 to 19 of knife members 12, 13 are threaded for receiving nuts 24, 25 which have each a side slot at 26, 27, the shanks of the blades being cut along their edges to correspond to the threads of the mentioned ends and allow the nuts to be turned upon said threaded ends. The upper blade 14 has a small slot 28 accessible when the knife is closed for being caught by the finger nail in order to swing said blade open, as will be further explained.

To permit the blades 14 and 15 to be opened or closed, when the slot 26 carried by the nut 24 is in register therewith, it will be noted that the threads, for a width sufficient to permit the blade shank to be rotated, are eliminated from the nut at a position opposite the said slot in the nut. Preferably, the blade shank 22, is threaded only along its outer edge adjacent its cutting portion the same being adapted to be engaged by the threads of the nut to lock the blade in open position upon rotation of said nut.

The knife members 12, 13 are externally reinforced by a pair of handle members 29, 30 of bone, horn, fibre or plastic, and at the rear, a strip of the same material is fitted at 31 between said handle members and preferably cemented thereto to close the rear of slot 11. At both ends, these handle members have reinforcing collars 32, 33 fitted into recessed portions 34, 35 therein. The front portions of these rein-

forcing collars are cut open at 36, 37 in line with the slot 11 previously referred to, in order to provide clearance for opening the blades. The front edge of handle member 30 has a clearance portion 38 allowing access to the finger nail slot 28 on blade 14 for opening said blade outward from the closed position shown in Figures 1 to 6. When the blades are closed within the handle, the nuts 24, 25 may be turned part of a revolution from register of their slots 26, 27 with the slot 11, so that the nuts retain the blade shanks in line with the ends of the handle members and normally prevent the blades from being opened accidentally.

When one of the blades is to be opened, say blade 14, the upper nut 24 is turned just enough to register its slot 36 with the blade 14 and handle slot 11, when the shank 22 will be free to rotate about pivot pin 20 by swinging blade 14 into the open position shown in Figure 7, at which time the nut may again be turned to obstruct the shank so that the blade is held firmly in its open position. The same procedure is followed for opening the other blade 15 and its locking nut 25 manipulated for releasing the blade and then holding it open. As soon as either blade thus opened should be closed, the respective locking nut is turned to allow the blade to swing inward through the slot in the nut into closed position, after which the nut is again turned to obstruct the blade shank and prevent opening of the blade thus closed.

The knife may have only one blade, if so desired, but if it has two as shown and described above, one may be made into a screw driver blade, if desired, or both blades may have cutting edges.

Manifestly, variations may be resorted to, and parts and features may be modified or used without others within the scope of the appended claims.

Having now fully described my invention, I claim:

1. In a folding knife including a bolt provided with a slot extending longitudinally of the same from end to end thereof, a threaded nut portion formed upon the bolt at one end provided with a slot registering with the slot in the bolt, a knife blade pivotally supported within the slot of the handle to extend through the slot of the bolt when in one position with respect to the handle, a locking nut threadedly engaging the bolt for co-operating with the latter to releasably hold the blade against movement relatively to the said locking nut being formed with a slot therein adapted to register with the slot of the bolt when the locking nut is in a certain position with respect to the bolt and screw threads formed upon the end portion of the knife shank adjacent the said pivotal support for engagement by the locking nut to secure said blade against movement when the blade is in either the open or closed position.

2. In a folding knife, a handle portion provided with a longitudinal blade receiving slot, a knife blade pivotally supported at one end within said slot, a nut having a slot adapted to be brought into registry with the slot in the handle threadedly engaging the handle portion adjacent the pivotal blade support, and threads formed on the knife blade which are adapted to be engaged by the nut to releasably secure the blade against movement relative to the handle when said blade is in the open or closed position.
